ANDREAS VANG, OF CHICAGO, ILLINOIS, ASSIGNOR TO JOHN MACKAY.

Letters Patent No. 86,114, dated January 19, 1869.

IMPROVEMENT IN KEYS.

The Schedule referred to in these Letters Patent and making part of the same.

To all whom it may concern:

Be it known that I, ANDREAS VANG, of Chicago, in the county of Cook, and State of Illinois, have invented a new and useful Improvement upon Keys; and I do hereby declare that the following is a full and exact description thereof, reference being had to the accompanying drawings, and the letters of reference thereon, making a part of this specification.

The nature of my invention consists in providing keys with a joint in the centre of the shank, and adjusting the handle-portion of it as a mould or case, to receive the bit-portion of the shank, and encase the same on two sides.

To enable others skilled in the art to make and use my invention, I will proceed to describe its construction and operation.

I construct my key of any metal suitable for keys, in any of the known forms, in two parts, A and C, of equal length, constructing the handle-portion of the shank in the form of a mould or case, C, adjusted to the form and size of the bit-portion, then unite the two parts with a rivet or screw, B, forming a joint, so

as to conveniently open and shut, similar to a pocket-knife, as convenience or use demands, and when shut, its length is shortened one-half; besides, the joint protects the key from bending or breaking when used where locks are not on a direct line with the escutcheon or key-hole, the key adjusting itself to that condition of things by means of the joint, thereby protecting it from bending or breaking, while, when closed, the case or mould protects the wards of the bit from wear and breaking.

What I claim as my invention, and desire to secure by Letters Patent, is—

Splitting the shank of a key, and jointing the same at the middle of the shank, and arranging the parts, so that one will fold upon the other, and shorten the length of the key one-half, without materially increasing its size, substantially as specified.

ANDREAS VANG.
